UNITED STATES PATENT OFFICE.

ISSIC H. GARSON, OF DETROIT, MICHIGAN.

ADVERTISING DEVICE.

1,378,538.

Specification of Letters Patent. Patented May 17, 1921.

Application filed July 12, 1917. Serial No. 180,122.

To all whom it may concern:

Be it known that I, ISSIC H. GARSON, a citizen of the United States, residing at Detroit, county of Wayne, State of Michigan, 5 have invented a certain new and useful Improvement in Advertising Devices, and declare the following to be a full, clear, and exact description of the same, such as will enable others skilled in the art to which it 10 pertains to make and use the same, reference being had to the accompanying drawings, which form a part of this specification.

This invention relates to advertising devices, and its object is an advertising device 15 provided with interchangeable transparent slides adapted to be shown one at a time. Another object of the invention is a means for lighting one side of the device at a time, and means for intermittently rotating the 20 device. These and other objects and the several novel features of the invention in its preferred form are hereinafter more fully described and claimed and shown in the accompanying drawings in which—

25 Figure 1 is an elevation of the device.

Fig. 2 is an enlarged vertical section of the lamp structure shown in Fig. 1.

Fig. 3 is a section showing the means for holding the advertising matter in position 30 within the lamp.

Fig. 4 is an elevation of the holder for the advertising matter.

Fig. 5 is a section therethrough.

Fig. 6 is a top view of the device with the 35 top plate removed.

Fig. 7 is a plan view of the mechanical means for rotating the device which is incased within the base thereof.

Fig. 8 is a section on line $x-x$ of Fig. 7.

40 Fig. 9 is a section on line $x-x$ of Fig. 3.

Similar characters refer to similar parts throughout the drawings and specification.

The device consists of a base 1 upon which is mounted a lamp structure, adapted to be 45 rotated by mechanism contained with the base as hereinafter described. The lamp is made up of a base part 2 and a top part 3, fitting thereon. As will be noted from Fig. 1 the part 2 is supplied with rectangular apertures 4 which are adapted to receive a holder 5 as shown in Figs. 4 and 5. This holder 5 is adapted to contain two panes of glass between which is a celluloid film containing advertising matter, pictures, or other 50 matter to be displayed. This holder 5 with the glass and film therein may be lifted by

the handle 6, and by removing the top 3 of the lamp it may be set in the rectangular opening 4 in which place it is held in guideways, it being understood that there are four 60 such rectangular openings 4 about the part 2 of the lamp. About the apertures 4 is a scroll work 7 of any desired ornamental design, and by placing different colored glasses behind the said scroll work a pleasing result 65 may be obtained. As will be noted more particularly in Figs. 2, 3 and 6, the top part of the lamp 3 is adapted to receive holders containing a film between two panes of glass and having advertising matter thereon, and 70 this glass is held in place adjacent the opening 8 by the spring hinge 9 which holds the lower edge of the holder in place. To hold the upper edge of the holder in place the device is provided with spring pressed retaining members 10 which are adapted to engage the top edges of the glass and hold them in place in the top part 3. As will be noted more particularly from Fig. 3, the part 2 is provided with a flange 11 and the 75 part 3 is provided with a flange 12 which is adapted to engage over the flange 11 and thus hold the part 3 in proper relation to the part 2. As will be seen more particularly in Fig. 2 the outer tube 13 of the lamp shaft is 80 secured to the lamp head by set screws 14, and thus the lamp head is rotatable with the shaft 13. An inner tube 15 is provided within the tube 13 upon which an incandescent lamp 16 is mounted and provided with 85 a shade 17 which throws light upon one side of the lamp at a time, the tube 15 being hollow to receive the electric wires of the incandescent lamp 16.

The mechanism for rotating the lamp is 90 shown more particularly in Figs. 8 and 9 which provides a driving means consisting of a motor 20 mounted on the base 1 of the lamp, the motor being provided with a shaft 21 having a worm 22 on the end thereof, 100 and the shaft 21 being provided with a bearing 23 on the opposite end of the motor. A worm gear 24 is mounted on the shaft 25 and in engagement with the worm 22, 105 and the said shaft 25 is provided with a worm 26 upon the opposite end thereof meshing with a worm gear 27 which is secured to the cam 28 on the pivoted shaft 29, which in turn is held in position by the set screws 30 and 31 and U shaped members 32 110 and 33. As will be noted more particularly in Fig. 9 the outer tube 13 is provided with

bearing rings 34 and 35 which are secured thereto by set screws. These bearing rings bear on the bushing 36 and are adapted to prevent vertical movement of the tube 13. 5 The inner tube 15 is secured by a set screw 37 to a small U shaped member 38 which is secured to the base 1 and thus holds the tube 15 from rotation. As will be seen from Figs. 8 and 9 on the tube 13 is secured 10 a cam 39 having rounded sides 40 thereon on the same radius as the cam 28 on the shaft 29. Slots 41 are provided in the cam 39 and pins 42 are provided on the gear 27, the cam 28 being also provided with indented 15 portions 43. Thus it can be seen that the motor 20 rotates the shaft 21 thus rotating the worm 22 which in turn rotates the worm gear 24 and the worm gear 27 and the cam 28, which is secured to it, though the cam 20 28 is rotated very slowly. Thus it can be seen that by rotation of the cam in the direction of the arrow shown in Fig. 7 the pin 42 will engage in a slot 41 of the cam 39 and as the pin 42 moves the end 44 of 25 the cam moves into the indentation 43 and is then moved out which turns the cam 39 one-fourth of a turn and allows the next face 40 to move in contact with the face 45 of the cam 28. Thus by this mechanism the 30 lamp is turned one-fourth of a turn and then stopped for a sufficient time to allow the advertising thereon to be read whereupon it is rotated another quarter of a turn and stopped again. Thus by use of the 35 shade and means for rotating the lamp a quarter of a turn at a time only one side of the lamp containing advertising matter is displayed at a time and as the lamp has two parts containing four sides each, eight different advertising signs may be used. By 40 taking the holder, glass, and film out of the lamp a new film may be inserted thus allowing a new picture to be shown, both the top 3 and bottom 2 of the lamp being adapted to receive new advertising matter. It 45 can thus be seen that a great variety of subjects may be kept on hand for advertising and that by changing the advertising, continually different subjects are shown.

50 From the foregoing description it be-

comes evident that the device is an improvement on the well known type of advertising devices as the advertising matter in each part of the lamp may be changed an unlimited number of times and thus present a new sign as often as desired.

Having thus briefly described my invention, its utility and mode of operation, what I claim and desire to secure by Letters Patent of the United States is—

1. An advertising device for holding a series of transparent films for display comprising a several sided lamp structure having a base part open at the top and a separable top part, each side of the base having an opening therein and being provided with grooves on each side of the opening interiorly of the base and in parallel relation for supporting the film, said top part also having apertured sides corresponding in number to the number of apertured sides of the base providing a cover therefor, spring-actuated members on the upper and lower ends respectively on each of the apertured sides of the top interiorly thereof adapted to hold a transparency, and an illuminating means within the structure.

2. An advertising device for holding a series of photographic films for display comprising a several sided lamp structure having a base part open at the top and a separable top part to permit introduction of the films, each side of the base having an opening therein through which a film may be exposed to view and each side of the top part having similar openings therein, companion sides of the top and base being oppositely inclined toward a common vertical center line, said base and top each being provided with means for supporting a film in position relative to the aperture, an electric lamp held in stationary position within the structure, a stationary shield adapted to project light through one side only of the base and top at a time, and means for rotating the structure about the lamp to display the films successively.

In testimony whereof I sign this specification.

ISSIC H. GARSON.
